UNITED STATES PATENT OFFICE.

GEORG AMRHEIN, OF MUNICH, GERMANY, ASSIGNOR TO THE FIRM OF DR. WILDSCHE BUCHDRUCKEREI GEGR. PARCUS, OF MUNICH, GERMANY.

MACHINE FOR PERFORATING STRIPS FOR SINGLE-TYPE-CASTING MACHINES.

1,158,767.

Specification of Letters Patent.

Patented Nov. 2, 1915.

Application filed June 30, 1915. Serial No. 37,404.

To all whom it may concern:

Be it known that I, GEORG AMRHEIN, citizen of Germany, residing at Munich, Bavaria, Germany, have invented certain new and useful Improvements in Machines for Perforating Strips for Single-Type-Casting Machines; and I do hereby declare the following to be a full, clear, and exact description of the invention, such as will enable others skilled in the art to which it appertains to make and use the same.

The present invention relates to the manufacture of perforated strips for single-type-casting machines.

15 The present invention consists of a device for manufacturing such perforated strips and is mainly characterized by the fact that the marginal perforations are made by means of the pin wheels of the feed mechanism, advancing the paper strips and in one 20 operation with the keys. For this purpose the unperforated paper strip is guided over a loosely revolving roller, which presses the paper strip against the teeth of the said pin 25 wheels.

In order to render the present invention more easily intelligible reference is had to the accompanying drawings.

Figure 1 shows diagrammatically partly 30 in section and partly in side view an apparatus, according to this present invention, while Fig. 2 is a section on line A—B of Fig. 1.

Referring to the drawing *a* is the standard 35 carrying the apparatus. *b* is a supply roll and *d* an unperforated paper strip, wound off the said supply roll *b* and *e* is a winding spool, upon which the paper strip *d'* is wound again after it is perforated. *f* are 40 jaws, attached to the sides of the standard *a* and *g* are the pin wheels of the feed mechanism, said pin wheels being loosely rotatable and mounted on either of the said jaws *f*, and advancing with their teeth the paper strip 45 as soon as it is perforated. Between the pin wheels *g* there is provided a die cylinder *h*, which is stationary and open at the top. This die cylinder *h* serves for the letter perforation and receives the waste material 50 from the paper strip being pushed through by the punch *i*. In front of the pin wheels *g* a sleeve *k* is loosely located, which in the path of the pin wheels *g* is provided with circumferential apertures *1*, in which

the teeth of the pin wheels engage in such a 55 manner that the said pin wheels *g* and the sleeve *k* form, so to say, a gear, between which the unperforated paper strip *d*, which extends over the width of the sleeve, is passed. The sleeve *k* is loosely rotatable 60 around an axle *m*, which is provided at its two ends with collars *n*, which in the path of the apertures *1* contain each a circular groove *o*, which is so deep that no resistance is offered to the pin wheels *g*. The collars *n* 65 may be arranged more toward the middle so that then the grooves *o* may be dispensed with.

The sleeve *k* and its bearing are preferably detachable and the sleeve *k* may be 70 spring pressed so that it may be yieldingly forced against the pin wheels. For this purpose the axle *m* is journaled in two plates *p* arranged sidewise of the jaws *f*, preferably in rearwardly open slots *r*. The plates *p* 75 are loosely suspended on a cross bar *s*, so that when the plates *p* are turned forward the sleeve *k* is moved away from the pin wheels *g* and may be removed. *t* are adjustable springs, which act against the plates *p* 80 and the other end of which is attached to the standard *a*, so that the suspended parts *p*, *k* may be pressed against the pin wheels.

In front of the sleeve *k* there is preferably provided a guiding roller *u*, which is 85 positioned in the plates *p* and by means of slantingly upwardly directed slots *v*, is rendered capable of rotation and of being lifted.

The unperforated strip *d*, being wound off 90 the roller *b* is passed over the under side of the roller *u*, over the upper side of the sleeve *k*, between the latter and the pin wheels *g* and finally to the winding spool *e*. As soon as the feeler apparatus is set into 95 operation the teeth of the pin wheels *g*, engaging the aperture *1* of the sleeve *k*, are forced into the unperforated paper strip 100 and impress the two rows of holes, which are situated near the edges of the paper strip. Those teeth of the pin wheels, which are 105 in front of the teeth effecting the perforation, at once enter the holes *w* and advance the paper strip. As the toothed wheels of the single-type-casting machine coincide with the pin wheels *g*, the teeth of the former enter the holes *w* quite exactly, so that the paper strip is guided more exactly

than before. And this for the reason that the teeth of the pin wheels *g* do not cut holes, allowing more or less play, but such holes, which exactly correspond to the form 5 of the teeth, and which fit exactly the teeth of the ratchet-wheels of the casting machine. Should any jerking advancing movement occur when winding off the paper strip, or should the latter be stopped or hemmed this 10 will be compensated by the yieldingly positioned guiding roller *u*.

By arranging the guiding roller *u* so as to be capable of being lifted it is possible to use the weight of this roller for winding 15 up the paper *b* automatically in that the roller *u*, which at the step-wise movement of the paper strip *d*, *d'* is always somewhat lifted, falls down again in the slots *v* and thus draws the paper strip from the sup- 20 ply roll *b*.

Paper waste and the like may be removed from the circular grooves *o* by raising the sleeve *k* away from the pin wheels *g* and then brushing such waste into the interior, 25 *x*, of the sleeve *k* or into a separate receptacle, as desired.

I claim as my invention:

1. In apparatus for the purpose set forth, 30 the combination of a supply roll adapted to support a reel of imperforated material, a winding spool adapted to receive said material after perforation thereof, pin wheels arranged between said roll and said spool, and a sleeve adjacent to said pin wheels, 35 said sleeve having perforations into which the teeth of said pin wheels enter, whereby said pin wheels are adapted to simultaneously feed said material and perforate the

same in its passage from the supply roll to the winding spool. 40

2. In apparatus for the purpose set forth, the combination of a supply roll adapted to support a reel of imperforated material, a winding spool adapted to receive said material after perforation thereof, pin wheels 45 arranged between said roll and said spool, a sleeve adjacent to said pin wheels, said sleeve having perforations into which the teeth of said pin wheels enter, and means for yieldingly pressing said sleeve toward 50 said pin wheels, whereby said pin wheels are adapted to simultaneously feed said material and perforate the same in its passage from the supply roll to the winding spool. 55

3. In apparatus for the purpose set forth, the combination of a supply roll adapted to support a reel of imperforated material, a winding spool adapted to receive said material after perforation thereof, pin wheels 60 revolvably mounted between said roll and said spool, a sleeve adjacent to said pin wheels, said sleeve having perforations into which the teeth of said pin wheel enters, whereby said pin wheels are adapted to simultaneously feed said material and perforate 65 the same in its passage from the supply roll to the winding spool, and a yieldingly positioned guide roller for the material in advance of said sleeve.

In testimony whereof I hereunto affix my 70 signature in the presence of two witnesses.

GEORG AMRHEIN.
